UNITED STATES PATENT OFFICE.

JOHN DICKER, OF NEWARK, NEW JERSEY.

PENCIL-CASE.

SPECIFICATION forming part of Letters Patent No. 325,325, dated September 1, 1885.

Application filed November 26, 1881. (No model.)

To all whom it may concern:

Be it known that I, JOHN DICKER, of Newark, in the county of Essex and State of New Jersey, have invented certain new and useful 5 Improvements in Cases for Pencils, &c., of which the following is a specification.

My invention relates to cases for pencils and similar implements; and the invention consists in a novel construction of the barrel 10 or body of the case, as hereinafter more fully set forth.

Figure 1 is a side elevation of a magic pencil having its case made on my plan. Fig. 2 represents the covering of the case spread out 15 or developed on a plane to more clearly illustrate the same. Fig. 3 is a perspective view of the body of the case detached, and Figs. 4 and 5 are longitudinal and transverse sections, respectively, enlarged to more clearly show 20 the parts.

To construct a case for pencils and similar implements on my plan, I first prepare the outside covering, and the material which I prefer to use is what is known as "pearl shell" 25 or "mother-of-pearl," and this I first saw into narrow triangular strips of the proper length, as indicated at *a* and *b* of the several figures. These strips are, by means of suitable tools, made straight, and either flat or concave on 30 their under side, according as they are to be applied to a polygonal or a round tube, both styles being used for this purpose.

Having prepared a series of these triangular strips of various colors or shades, I take a thin metal tube, *l*, which is to form the foundation or lining of the case, and cement thereon a layer of paper or cloth, as indicated by *n*, Figs. 4 and 5. Then upon this I arrange a series of the triangular slabs of shell, taking 40 care to place first a light-colored slab, *b*, and next to that a dark or different colored slab, *a*, and alternating their points or narrow ends, as shown in Figs. 1, 2, and 3, until enough slabs have been thus applied to cover the 45 tube, the slabs of course being cut of such a width as to form a cylindrical covering for the tube *l* and its covering of paper or cloth *n*. The slabs *a* and *b*, when finally applied,

are cemented to the layer *n* of paper or cloth, and also to each other, and they are further 50 secured in place by the caps *c* and *d*, which fit over the ends of the slabs, as shown in Fig. 4, in which I have represented the barrel thus formed as being shouldered or reduced slightly in external diameter at each end, 55 though it is obvious that this may be omitted if desired, and the caps be made to fit over the exterior of the slabs at each end, and thus bind them together the same as hoops bind the staves of a barrel; and, if desired to render it still more ornamental, small metal bands or hoops, either plain or ornamented, may be made to embrace or inclose the slabs 60 at other points between their extremities.

By this method of construction I am enabled 65 to produce a case in which the sections or slabs of shell composing the exterior are firmly secured in place, so as not to be liable to become loosened by use, and which may also be rendered highly ornamental.

I am aware that pencil-cases have been made of alternate strips of shell and metal of uniform width, and that cases have been made of strips of shell of uniform diameter with narrow strips of muslin inserted under each 75 joint, and I do not claim either of these; but,

Having thus described my invention, what I claim is—

1. The herein-described case for pencils and similar implements, consisting of the tube *l*, 80 having a layer of fibrous material, *n*, cemented thereto, and an outer layer composed of triangular slabs of shell or similar material having their narrow ends arranged alternately in opposite directions with the overlapping 85 caps *c* *d* applied thereto, substantially as shown.

2. The combination of the tube *l*, the layer of paper or cloth *n*, and the triangular slabs of shell, arranged substantially as and for the 90 purpose set forth.

JOHN DICKER.
